UNITED STATES PATENT OFFICE.

GEORGE W. CAMPBELL, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Application filed October 27, 1921. Serial No. 510,726.

To all whom it may concern:

Be it known that I, GEORGE W. CAMPBELL, a citizen of the United States, residing in Hartford, in the county of Hartford and 5 State of Connecticut, have invented certain new and useful Improvements in Typewriting Machines, of which the following is a specification.

The present invention relates to sound-deadening casings for typewriting machines; that is to say, to casings in which the machine may be placed and operated with a minimum of noise. In casings of this character, provision is necessarily made 10 for the protrusion of the keyboard section of the machine through the front wall of the casing in order that the keys may be accessible to the operator; and provision is also made for the protrusion through the 15 casing and for the travel therealong of the operating arms, which are mounted on the carriage and move therewith on the machine, such as the line-space lever, the carriage-release-lever, and the carriage-re- 20 turn-arm. To permit of placement of the keyboard extension, while nevertheless providing a sound-proof front wall for the casing, the front wall has a hole therein, through which the keyboard extension is 25 swung while the machine is being inserted 30 through the top of the casing, the front of the machine itself being utilized to close that part of the hole which is above the keyboard when the machine is finally in 35 place. The present invention more particularly relates to the latter type of casing, although it will be found that in many of its features it is not so restricted.

Casings of the character mentioned have 40 their walls lined with sound-deadening members, variously shaped and secured; and preferably have a window through which the printing may be observed, so that a "visible" typewriter remains such, when 45 used in the casing. The casing may also have its own sound-deadening floor. The present invention relates in part to these features of construction. In what is perhaps its more important aspect, however, 50 the invention has reference to the construction of the casing shell and frame.

The invention aims to make rigid the body, having no top or bottom, and to insure that the large hinged cover shall fit 55 closely in order to confine the noise, and to

secure such accuracy of construction as to permit rapid and easy operation of the carriage with its handles protruding through the sealed slot. The invention also aims to support the heavy typewriting machine 60 properly upon the thin and weak sheet-metal walls, without tearing away from the walls, or bending or distorting the same.

In carrying out the invention, the back, 65 sides and front are made of a single rigid unjointed die-cast piece of metal, each element reinforcing the other three. This body will not become skewed when subjected to ordinary rough usage, and hence the cover will always fit, and sound will 70 not therefore escape. The large cover, with its heavy glass pane, is sustained upon the side portions of the body, as the entire front of the cover must be out of contact with the body, this being the position of the slot 75 which is sealed by the soft tubes, and through which the carriage handles travel. The die casting extends at its top portion entirely across the front of the machine, counteracting the tendency of the heavy 80 cover to spread apart the sides of the body. An unbroken, unjointed, stiff, upper box-like portion is combined with a lower unbroken, unjointed, stiff box-like portion, 85 these two portions being joined to each other by a plate-like body-portion which is integral with both said top and bottom portions, the body comprising four integral corners conducing to rigidity.

A feature of the invention is the provision 90 of die-castings, one to form and comprise the body-portion of the casing, and another to form and comprise the cover therefor. The number of parts, the joints to be closed, and the time and labor involved in 95 assembling are thus all brought to a minimum. Moreover, since the castings are jointless, and are of great rigidity, although thin and light, the casing will be durable as to its sound-deadening qualities despite 100 strains and shocks incident to rough handling. Not only need the castings have no joints to be opened by strains, but their rigidity prevents loosening or displacement 105 of the lining-members under external strains.

Another feature of the invention is the provision of re-enforcing ribs formed in the casting operation, which ribs are preferably disposed along the top and bottom 110

edges of the casing-body; along the bottom edge of the cover; and along the edges of the openings in the walls of the castings. A further feature of the invention is the adaptability and use of these ribs for other purposes, such, for instance, as anchorages for the lining-members. Screws for holding the lining-members; screws for holding a felt-bottom for the casing; and screws for holding cushions for closing the slot along which the operating levers of the machine travel, may, any or all of them, be threaded into the ribs to a depth not obtainable in other parts of the casing, and their grip on the casing thus assured.

Other objects of the invention are the provision, as part of the cover-casting, of a frame for a transparent window-pane therein; the provision, as parts of the cover and body castings, of seats for the cushions which close the slot for the operating levers; the provision, as parts of both castings, of flanged interior offsets to serve as abutments and retaining devices for the lining-members; and the provision, as part of the body-casting, of lugs or devices for positioning the feet of the machine within the casing. A feature of the invention is the function which the window-frame, cushion-seats, and other parts just referred to have as re-enforcing ribs by virtue of being integral parts of the castings; or, conversely, the functions as window-frame, cushion-seats, etc., to which the re-enforcing ribs may be adapted.

The various objects and features of the invention are preferably embodied in a casing, the body-casting of which is an elongated, rectangular shell, open at top and bottom, and ribbed around the top and bottom edges; and the cover of which is arched to accommodate the carriage of the machine, and is ribbed at its front edge and along intermediate lines which define a window-frame.

Other features and advantages will hereinafter appear.

In the accompanying drawings,

Figure 1 is a perspective view of the sound-deadening casing showing it closed.

Figure 2 is a perspective view of the sound-deadening casing showing the cover sprung to its open position.

Figure 3 is a side view vertical section of the casing.

Figure 4 is a top plan view showing part of the carriage and the operating arms and levers thereon.

Figure 5 is a sectional side view of the casing showing the manner in which the machine is inserted into said casing.

Figure 6 is a detail sectional plan view of the right-hand end of the casing showing, among other features, the means by which the machine is positioned therein.

Figure 7 is a front view partly sectioned of the right-hand end of the casing.

Figure 8 is a rear perspective view of the detachable plate at the front of the machine.

The Underwood standard typewriting machine comprises a main frame 10, supported by feet 11 upon a base, and is provided with a forward extension 12, in which are positioned banks of keys 13, for operating type-bars 28, to cause types 29 carried thereby to print against a platen 15, journaled in the end walls 16 of a platen-frame. The platen-frame forms part of a carriage 20, mounted for letter-feeding movement upon a front rail 51 and a rear rail 21, fixed to the main frame 10. The carriage is provided with various forwardly-extending levers or arms, such as a line-space-lever 23, a carriage-return-arm 24, and a carriage-release-lever 25.

For deadening the sounds occurring in the typing operation, there is provided a sound-deadening casing or hood, comprising a body-part 30, and a cover-part 31, hinged to the body-part at 32. The body-part comprises a rear wall 35, side walls 36 and a front wall 37. To permit of operation of the type-keys from outside of the casing, the front wall 37 has a substantially rectangular opening 38, through which passes the forward extension 12 of the machine, so as to expose the banks of keys 13. To provide for letter-feed movement of the carriage within the casing, and to allow room for the paper which hangs down at the rear of the paper-shelf and travels with the carriage, the body-portion of the casing is somewhat wider at its base than is the machine, and, as shown in Figure 2, is flared upwardly and laterally at 39 to the full width of the cover-portion; in which latter, the carriage has its throw between extreme positions. To each side of the opening 38 in the front wall of the body-portion 30 of the casing, there is therefore presented a wall-portion 40 of somewhat triangular shape; and, connecting the front wall-portions 40 above the opening 38, the front wall 37 is in the form of a strip 41, which is flared forwardly from the vertical, at 42, and is then turned vertically upward, as at 43. Below the opening 38 in the body front wall, the wall also takes the form of a horizontal strip 44, which is likewise offset forwardly just below the base of the machine.

The casing is a die-casting; or, rather, is comprised of two die-castings, one of which comprises the body-part 30; and the other the cover-part 31. A bead 45, which forms a part of the casting 30, extends entirely around the same at the base thereof, and serves as a rib-re-enforcement. The bead 45, being on the outside, serves also as ornamentation. For each of the front casing-portions 40, there is provided a lining-piece

47 of felt or other sound-deadening material. These lining-pieces 47 conform to the shape of the parts 40, and are mitered at their upwardly-curved lateral edges 17, 5 see Figure 6, to fit with a similar mitering on lining-pieces 48 for the sides of the body-portion. The forward mitered edges of the lining-pieces 48, therefore, hold the front felt pieces 47 at their outer edges. For holding the lining-pieces 47 at the edges of the opening 38, there is provided a vertical metal strip 49, see Figure 6, on the inside of each of the parts 40, which strips are riveted as at 46, or which may be soldered, 10 brazed or otherwise attached, to the parts 40 in any suitable manner, and have threaded holes therein to receive screws which pass through the lining-pieces 47 from the inside. These strips 49 also serve as re-enforcements 15 for the front wall at the opening 38. For holding the lining-pieces 47 to the casing front portions 40, at their upper edges, there is provided a strip 52, see Figure 3, which extends over the opening 38 entirely across 20 the front of the casing-body, and between which and the front of the casing-body the lining-pieces 47 are set. Screws 53 pass through the strip 52 and through the linings 47, finally to be threaded into the wall 25 of the casing. Also held at its upper edge, in like manner, by other screws 53, between the strip 52 and the front of the casing, over the opening 38, is a felt strip 54. The lower edges of the lining-pieces 47 overlie the re-enforced or beaded lower front edge 45 of the casing, and are held to the same by screws 22 which pass through these lining-pieces from the inside and into the beaded casing-rim. The bead allows such depth of 30 screw-hole as will provide a firm hold for the screws.

Below the opening 38 the front of the casing is lined by a strip of felt 55, the lower edge of which is attached to the re-enforced or beaded lower edge 45 of the casing by other screws 22; and the upper edge of which normally projects slightly above the upper edge of the front casing-strip 44 below the opening 38. To permit operation of 45 the space-bar-supporting levers 87 and the shift-lock-release-lever 94, and to receive the side frame-pieces 163 of the machine, the front piece 44 of the casing below the opening 38 is slotted, as at 87^a, 94^a and 163^a, respectively; and the lining-piece 55, therefore, has slots or cuts in registration with the slots 87^a, 94^a and 163^a. Screws 58 pass through the strip 55, between the slots therein, and into the front wall of the casing 50 to hold the lining-strip 55 in place. The upper edge 55^a of the front lower lining-strip 55 above the front lower casing-portion 44 is free and flexible, so that, when the machine is in place, this flexible edge 55^a is forced down by the shift-lock-release-rod 55 55^b 55^c 55^d 55^e 55^f 55^g 55^h 55ⁱ 55^j 55^k 55^l 55^m 55ⁿ 55^o 55^p 55^q 55^r 55^s 55^t 55^u 55^v 55^w 55^x 55^y 55^z 55^{aa} 55^{bb} 55^{cc} 55^{dd} 55^{ee} 55^{ff} in place in the casing, see Figure 6, an extra thickness of lining is desirable at the side edges of the opening 38. This extra thickness is effected by the placement of two 5 narrow strips of lining-material 69 between the lining-pieces 47 and the front casing-body-portions 40.

Cast integrally with the casing front at the lower edge thereof, see Figure 6, are two 10 lugs 70 having recesses 71 in their rear edges to receive and position the front feet 11 of the machine, and to permit the machine to be brought forward in the casing, so that the front plate of the machine may 15 abut the front wall of the casing.

A base-piece of sound-proof material 74 is secured to the beaded lower rim 45 thereof by screws 75 at the front, sides and rear of the casing. The rear wall 35 of the casing-20 body is preferably provided with a one-piece lining 76; and, as heretofore stated, the end walls 36 of the casing-body are provided with lining-members 48, which are 25 also preferably one-piece members. It has been noted that the side lining-members 48 are mitered where they engage the front lining-members, so that the front and side lining-members hold each other in place where their edges come together. The side 30 lining-members 48 and the rear lining-members 76 are likewise mitered at their abutting edges for the same purpose. Thus, these lining-members, except at their upper and lower edges, hold each other in 35 place.

Screws 77, passing through the lining-material from the inside face thereof, are threaded into the beaded rim of the side and rear walls of the casing to hold the side 40 and rear lining-pieces 48 and 76 at their lower edges. A metal strip 79 extends along the top edge of the rear lining-member 76 on the inner face thereof; and screws 80, passing through the strip 79 and through 45 the lining-member 76, thread into the metal of the casing to hold the rear lining-member 76 at its upper edge. Similar strips of metal 81 and screws 82 hold the top edges of the side or end lining-pieces to the casing-50 body.

The casing-cover, at its rear, and for a distance over the top thereof, has a sound-proof lining-member 88 which is held in place at its lower edge by screws 89 which 55 pass therethrough and which thread into the wall of the cover. The cover-portion, at the rear thereof, and where it reaches over the type-writer-carriage, is also provided with a smooth interior facing-piece 90, so that the paper on the typewriter-carriage 60 may not be caught and twisted or crumpled by contact with the felt. The screws 89, which serve to hold the lining-member 88, at the lower edge thereof, also serve to hold 65 the lower edge of the facing-piece 90. The

facing-piece 90 extends slightly below the top edge of the body-portion to prevent the paper from being caught between the body and cover.

A large rectangular opening 91 in the forward upper wall of the cover serves as a window through which the writing may be observed. As shown in the drawings, the cover around the periphery of this opening is re-enforced by a depending rib 92, cast 75 integrally therewith. This rib serves as the frame for a transparent pane 93, which may be of heavy glass. A flange 86, which defines the opening 91 and which, as an integral part of the cover-casting, forms 80 a shoulder with the rib 92, serves as a seat for the pane 93. A strip 95 of suitable shock-absorbing material, such as leather, lies between the pane 93 and its seat 86. Two strips of metal 96, one 85 at either end of the window, see Figure 7, are screwed as at 97 to the rib 92 inside of the cover; and, when in place, overlap the end edges of the pane to hold the latter in place. The shock-absorbing 90 material 95 is shown as brought around the ends of the pane, as at 98, between the pane and the holding strips 96. The cover-lining-piece 88 abuts the rib 92 at the rear of the window. The facing-piece 90 is screwed at 95 its forward edge at 98^a to the rib 92, and thus holds the lining 88 where the latter abuts the rear of the window-frame.

The ends or sides of the cover are provided with sound-deadening linings 88^a, 100 which may be continuous with the lining-member 88, except where cut away for shaping purposes. The lower edges of the cover side lining-pieces 88^a are held in place by metal strips 99, which extend therealong 105 from near the front of the casing-cover to the rear thereof, and which lie against the lining-pieces 88^a on the inside face thereof. Other strips 99^a, parallel to the strips 99, 110 are riveted to the inner faces of the cover side members. Screws 100 pass through strips 99, through the lining-pieces 88^a and thread into the strips 99^a; thus holding the edges of the lining-pieces 88^a. To render 115 sound-proof the casing-cover at the portions 101 thereof at the sides of the window, the side lining-pieces 88^a are provided with ears or flaps 102, which are turned over from the upper parts of the pieces 88^a to follow the line of the cover to the rib 92 at the sides of the window. The edges of these ears or flaps 102, where they abut the rib 92, are held in place by the strips 96 which hold the window-pane.

At its front forward edge, the cover-casting is off-set downwardly at 103 and terminates in a bead or enlargement 104 which extends horizontally the full width of the cover, along the front of the casing. This bead 104 serves as a re-enforcement for the 120

cover, and also serves as part of the seat for the upper of two cushions. These cushions are shown as tubes 109 of rubber or other yieldable, flexible material, each supported in the fold of a strip 110 of flexible material, such as felt, the ends 111 of the strips 110 being brought together between the front or downward offset 103 of the cover and a metal strip 112. The inner face 10 of the bead 104 is shaped as at 106 to the curve of the cushion, and the strip 112 is curved rearward as at 113, also to conform to the curve of the cushion. A metal strip 114 lies against, and runs lengthwise of, the 15 flat part of the strip 112. Screws 115 passing through the metal strips 112 and 114, and the ends of the felt cushion-strips 110, thread into the beaded offset 103 of the cover and hold the upper cushion in place. 20 The upper and lower cushions 109 are normally in contact to prevent escape of sound except where various operating levers and arms project between the cushions from the inside to the outside of the casing; the 25 cushions being resilient to permit of actuation, and movement with the carriage, of these various levers and operating arms.

The lower cushion 109 is supported in substantially the same manner as the upper cushion. A re-enforcing bead or enlargement 116 in the casting of the casing-body extends horizontally lengthwise of the upper edge of the front wall 43 of the casing-body. Its upper rear edge is shaped as at 117 to 30 the curve of the lower cushion. A metal strip 118 similar to the strip 112 lies against the abutting edges 111 of the cushion felt piece 110, and is bent rearward to conform to the shape of the cushion; a seat thus being formed by the bead 116 and strip 118. A flat metal strip 83 lies against the rear face of strip 118; and the screws 53, which hold the upper edges of the front lining-pieces, pass through the strips 118 and 83 to 45 hold the lower cushion.

At the sides of the casing, the cover, when closed, is supported by the lining-members; that is to say, the lower edges of the side or end lining-members 88^a of the casing-cover rest upon the upper edges of the side or end lining-members 48 of the casing-body. At its front, the cover rests on the lower cushion 109. The weight of the cover effects a substantially sound-proof joint between the abutting edges of the felt. If desired, the metal of the body may, of course, be shaped to provide rests for the cover; but, where the lining-members are of sufficient thickness, and are properly attached, this 50 is not ordinarily necessary.

To conceal the abutting side pieces of felt, and to protect the joints, and to add to the appearance of the casing, the side walls of the cover, as indicated at 84, overlap the 65 top side-edges of the casing-body when the

cover is closed; and these overlapping cover-parts 84 are turned slightly outward, so as not to have contact with the casing-body. In order that the ends of the cushions 109 may be covered, the side walls of the cover are extended forward of the cushions, and have ears 85 turned laterally to overlie the cushions at the front of the latter for a slight distance. The rib 116 at the top front-edge of the casing-body is discontinued where the ears 85 are to overlap the front of the casing-body, so as not to interfere with the ears in the closing of the casing.

The cover is held open, and is assisted in its opening movement, see Figure 5, by two devices, one at each side of the casing, and each comprising a rod 119, pivoted at 120 to a bracket 121, secured to the inside of the cover end plate, the brackets 121 having offsets 122 which pass through cuts in the cover lining-members 88^a. The rods 119 slide in cylinders 123, which, see Figures 3, 5 and 7, have ears 125 pivoted at 124 to brackets 126. The brackets 126 are secured to the side plates of the casing-body and project through cuts in the end lining-members 48 of the casing-body. Within the cylinders 123, the rods 119 are provided with collars or pistons 127^a, against each of which bears the end of a coiled spring 127; the other end of which spring has bearing upon the lower forward end of the cylinder. When the cover is closed, the spring is compressed. As the cover is lifted, the pressure of the spring on the pistons 127^a tends to throw the cover upward and backward; and, therefore, to assist in the opening thereof. As a buffer, and to prevent strains and shocks on the parts by too violent an opening of the cover, there is also, within each of the cylinders 123, a spring 128. The springs 128 lie between the pistons 127^a and caps 129 on the upper rear ends of the cylinders. As shown in Figure 5, the caps 129 are shouldered to rest against the ends of the cylinders and have annular flanges 130 which fit within the cylinders. Set-screws 130^a hold the caps in place on the cylinders. The annular flanges on the caps are of such size as to provide a chamber between the same and the plungers or rods 119, for the springs 128; and the pistons 127^a are also preferably cup-shaped to receive the springs 128. As contradistinguished from the springs 127, the springs 128 are not under compression when the cover is closed. As the rods or plungers 119 move backward with the pistons 127^a in the opening of the cover, however, the springs 128 are compressed, 110 and thus act as buffers. The cover may be opened and closed by means of a handle 50, screwed to the front piece 105 thereof.

In the Underwood standard typewriting machines and in other typewriting machines,

the line-space-pawl and operating lever therefor are returned to normal position after each line-space movement by a spring, ordinarily, suitable for such purpose.

5 Where, however, the line-space-lever, as in the present invention, is to project through the casing, and is to be moved between cushions 109, which resiliently bear thereon, it may be desirable to provide other than the means heretofore used, for returning the line-space-lever after actuation thereof. In other words, it may be desirable to provide extra power, for the return-throw of the line-space-lever, to overcome the friction exerted on that lever by the opposed resilient cushions 109. Accordingly, in the present invention, see Figure 4, there is provided an auxiliary spring 133 to assist the spring (not shown) which is ordinarily used to return the line-space-lever. In the Underwood machine, the line-space-lever 23 is, in effect, a bell-crank-lever, pivoted at 134 to the carriage-frame, one arm 135 of which bears upon the end of a slide 136 which carries the line-space-pawl. The spring 133 is shown as secured at one end to this slide-operating arm 135 and at its other end to a lug 138 on the front rail 139 of the carriage-frame. A lug 140 on the same rail of the carriage-frame limits the return-throw of the line-space-lever; and a plate 141 may be secured to the lugs 138 and 140, as by means of screws 142, to overlie the line-space-lever.

35 In the Underwood standard typewriting machine, the carriage is controlled by a pinion 144 which meshes with a rack 145 on the carriage. The rack 145 is movable into and out of engagement with the pinion 144 and lifted out of engagement with the pinion 144 when the carriage is to be released. A lever 146, pivoted at 147, controls the rack 145, so that, when the forward arm 148 of the lever 146 is depressed, the carriage is released. Ordinarily, the arm 148 carries a finger-piece 149 for actuating the lever 146. It will be noted, see Figure 3, that the forward arm 148 of the carriage-release-lever has a downward-and-forward movement.

50 It will also be noted that in the drawings the finger-piece 149 is shown as quite within the casing.

In order that the carriage-release-lever 146 may be operated from without the casing, there is provided, in the present invention, see Figures 2, 3 and 4, another lever 150 which may itself be termed the carriage-release-lever, and which may be pivoted, as at 151, indirectly to the front carriage-rail 139. The forward arm 152 of the lever 150 is bent downward and is then extended forwardly between the cushions 109; and, at its outer end, carries the finger-piece 25. The lever 150 has a lateral swing on its pivot 151. The inner arm 154 of the lever 150 is forked, as at 155, to embrace the vertically-disposed stem or finger-piece-portion 156 of the lever 146. The pivot 151 of the lever 150 is to the left of the lever 146, so that movement of the finger-piece 25 to the left causes the arm 148 of the lever 146 to be thrown down, and the rack 145 to be lifted out of engagement with the pinion 144, thus releasing the carriage. The fork 155 of the lever 150 allows for the loose play necessary to permit the lateral movement of the lever 150 to be translated into the vertical movement of the lever 146.

In the present invention, the carriage-release-lever 150 is not pivoted directly upon the typewriter-carriage, but is pivoted on an arm 157, which carries the finger-piece 24, for returning the carriage. The carriage-return-arm 157 is itself secured to the front carriage-rail 139; and, like the carriage-release-lever 150, is bent downward and then carried outward between the cushions 109. The finger-pieces 24 and 25 on the carriage-return-arm and the carriage-release-lever are adjacent one another, so that the carriage-return-arm may be engaged by the thumb, and the release-lever by the forefinger, to pinch the release-lever toward the carriage-return-arm; thus enabling the operator to release the carriage with his forefinger, and to control the return-movement of the carriage, while the same is thus held released, by the engagement of his thumb with the carriage-return-arm. By simply removing the screw 151, the auxiliary carriage-release-lever 150 may be detached; after which the carriage-release may be effected in the usual way by the finger-piece 149, when the casing is not used. The carriage-return-arm 157 is also of a special design for use with a casing; and it, also, may be removed at will. The plate 169, on which the arm 157 is formed, is held to the rail 139, see Figure 3, by a tongue-piece 170 which is held by screws 151 and 171 to the plate 169, and which is offset to engage the bottom of the rail 139. Set-screws 172 also assist in holding plate 169 to the rail 139. By removing the screws 151 and 171, the plate 169, arm 157 and lever 150 may all be removed.

Secured to the rear and side walls of the casing-body, see Figures 1 and 6, are two brackets 160, in the form of sheet-metal strips passing through cuts in the lining-members 76 and 48. These strips are set vertically, and each has a pocket 161 therein to receive one of the rear feet 11 of the typewriting machine. The typewriting machine is placed in the casing in the manner indicated in Figure 5, that is to say, it is tipped, so that the front extension 12 thereof may be passed through the opening 38 in the front wall of the casing-body, and is thereafter swung downwardly, the

- extension 12 being simultaneously swung forwardly until the rear feet 11 of the typewriter enter the pockets 161 in the brackets 160, and the front feet 11 the recesses 71 in the lugs 70. The pockets 161 are so positioned as to cause the front plate of the machine to abut the inner face of the casing front plate. In being thus placed in the casing, the side plates 163 of the machine 5 are dropped into the slots 163^a in that portion 44 of the front wall of the casing which underlies the opening 38. The weight of the machine, when the casing is on a stand, is carried by the front and rear feet 11. If, 10 when the machine is in place in the casing, the casing be lifted, the flexibility of the felt base-piece 74 allows the machine slightly to settle in its casing until the shoulders 165 at the rear feet of the machine come to 15 rest upon the top edge of the brackets 160, and until the lower edges 166 of the side plates of the machine come to rest in the bottom of the slots 163^a in the front plate of the casing-body. Thereupon the metal 20 framework of the casing relieves the base-piece 74 of the weight of the machine; and the casing, with the machine in position within the same, may be moved as a unit from place to place.
- 25 It will be noted that the offset or overhang 167 at the left-hand side of the casing-body, see Figure 1, is greater than the offset or overhang 168 at the right-hand side of the casing-body. This excess of overhang or space at the left-hand side of the casing-body is to allow for the throw of a clutch such as is used in the Underwood typewriting machine to release the platen from the 30 line-space mechanism. This clutch, otherwise known as the fractional line-space-clutch, in the Underwood typewriting machine is concentric with the axis of the platen, and is shiftable longitudinally outward to the left in the releasing operation.
- 35 It will be noted that the marginal stop-devices 175 are so located with respect to the upper front edge of the casing-body as to be conveniently operable when the cover is lifted. It will also be noted that the opening 38 in the casing front is such that the bichrome-shift-lever 176 and the margin-release-key 177 project therethrough, so as to be operable without lifting the cover.
- 40 Variations may be resorted to within the scope of the invention, and portions of the improvements may be used without others.
- 45 Having thus described my invention, I claim:
1. In combination, a typewriting machine 46 and a sound-deadening casing therefor; the casing comprising front, rear and side walls in a single casting; a movable cover; the front wall having an opening therein with a continuous periphery of such size and 50 contour that, upon insertion of the machine,
- in forward and downward tilted position, through the top of the casing when the cover is open, the keyboard extension thereof may be swung outward through said opening; and sound-deadening linings 70 for the walls and cover; and the machine having over the keyboard thereof a sound-deadening front plate, said front plate having an opening in its top portion to expose the types, and a plate 75 insertible in position to close said top opening to complete the closing of the casing, said insertible plate having means to catch upon the typewriting machine to retain it- 80 self in position thereon, and the type-writ- 85 ing machine being so positioned in the casing that the front plate of the typewriting machine lies against the inner face of the front wall of the casing.
2. A sound-deadening casing for a type- 85 writing machine, comprising, in a single casting, a top having re-enforcing ribs forming a window-frame; a sound-deadening lining for the top; and attached flanges extending from the tops of said ribs to hold in 90 position the edges of said lining and to engage the edges of a transparent pane in said window-frame.
3. A sound-deadening casing comprising, 95 in a single casting, a cover, and a re-enforcing rib extending horizontally and longitudinally of the front edge thereof; and a cushion secured to and extending lengthwise of the rib; the cushion defining the upper edge of a slot along which, when the machine is in the casing, the operating arms 100 on the machine carriage move as the carriage moves on the machine.
4. A sound-deadening casing comprising, 105 in a single casting, a body-portion, and a re-enforcing rib extending horizontally and longitudinally of the front upper edge thereof; and a cushion secured to and extending lengthwise of the rib; the cushion defining the lower edge of a slot along which, when 110 the machine is in the casing, the operating arms on the machine carriage move as the carriage moves on the machine.
5. A sound-deadening casing for a type- 115 writing machine, comprising a top and an offset window-frame therein, in a single casting; a transparent pane in said frame; a sound-deadening lining having strips extending along the sides of said window-frame; and strips secured to and running 120 along the sides of said frame for holding in place the pane and said strips of the lining.
6. A sound-deadening casing for a type- 125 writing machine, comprising a top and re-enforcing ribs therefor in a single casting; said ribs being shaped to serve as a window-frame; a transparent pane in said frame; a sound-deadening lining having strips extending along the sides of said window- 130

frame; and strips secured to and running lengthwise of said ribs at the sides of the frame for holding in place the pane and said strips of the lining.

- 5 7. A sound-deadening casing for a typewriting machine, comprising a body-part; a cover; and lining-pieces of felt or other sound-deadening material for the sides of the body and cover; the lining-pieces on 10 the cover abutting the lining-pieces on the casing body to support the cover when the casing is closed; and the side walls of the cover and body then overlapping to conceal such abutting edges of the lining-pieces.
- 15 8. A sound-deadening casing for a typewriting machine, comprising a body-part; a cover; lining-pieces of felt or other sound-deadening material for the sides of the body and cover; the lining-pieces on the cover 20 abutting the lining-pieces on the casing body to support the cover when the casing is closed; and the side walls of the cover and body then overlapping to conceal such abutting edges of the lining-pieces; and abutting 25 cushions on the opposing front edges of the cover and body, which cushions assist in supporting the cover, and provide a yielding slot along which the operating arms on the carriage of the machine may move.
- 30 9. A sound-deadening casing for a typewriting machine, comprising a body-part; a cover; lining-pieces of felt or other sound-deadening material for the sides of the body and cover; the lining-pieces on the cover 35 abutting the lining-pieces on the casing body to support the cover when the casing is closed; and the side walls of the cover and body then overlapping to conceal such abutting edges of the lining-pieces; and abutting 40 cushions on the opposing front edges of the cover and body, which cushions assist in supporting the cover, and provide a yielding slot along which the operating arms on the carriage of the machine may move; the 45 side walls of the casing cover being offset toward each other at the front to enclose the ends of the cushions.
10. In combination, a typewriting machine, a casing therefor, the machine having 50 a front wall with an arcuate opening to expose the types, the casing having a front wall with an opening to give access to the types, a removable plate which may be inserted between the front walls when 55 the casing is in position around said machine, said plate being slidable down behind the front wall of the casing and in front of the front wall of the machine, the edge of said plate overlapping the edge of the 60 arcuate opening in the front wall of the machine, and fingers on said removable plate to engage the front wall of the machine to locate said plate in its effective or closing position.
- 65 11. In combination, a typewriting ma-

chine, a casing therefor, the machine having a front wall, a front plate with an arcuate opening to expose the types, said front plate being secured to said front wall, the casing having a front wall with an opening to give access to the types, part of the opening in the casing being closed by said front plate of the machine, a detachable sound-deadening plate which may be inserted between the front wall of the 75 casing and the front plate of said machine, to close the arcuate opening in said front plate, and fingers on said detachable plate to locate the latter in position on the machine, said fingers engaging said front plate. 80

12. In combination, a typewriting machine, a casing therefor, the machine having a front wall with an arcuate opening to expose the types, the casing having a front wall with an opening to give access 85 to the types, a detachable plate which may be inserted between the front walls when the casing is in position around said machine, two fingers at the top of said plate to engage the machine to locate said plate, 90 and a hook-like extension at the lower part of said plate to prevent movement of said plate away from said machine.

13. A sound-deadening casing for a typewriting machine, comprising a body-part, 95 a cover having a cast front wall flared outwardly at its lower edge and provided with a channel of arcuate cross-section in the rear face of the flared edge, and a tubular cushion to rest in said channel. 100

14. The combination with a typewriting machine, of a sound-subduing cabinet within which the typewriting machine is fitted and by which it is supportable, said cabinet comprising a lower body-portion, and an 105 upper cover-portion hinged thereto in rear, a slot intervening between the front of the cover and the top of the body, through which slot extend controlling devices from the carriage, said slot sealed in a manner 110 to permit free travel of the carriage, said body-portion having a rear wall, a front wall, and overhanging side walls, all formed of a single rigid, unjointed, die-cast shell, making a continuous frame open at top and 115 bottom, an opening being provided in said front wall between the top and bottom, through which the keyboard of the typewriter protrudes, said front wall unbroken at its top and also unbroken at its bottom, the typewriting machine being insertable downwardly and forwardly into the body in a manner to thrust the keyboard portion forwardly through said opening in the front wall, as set forth. 120

15. The combination with a typewriting machine, of a sound-subduing cabinet within which the typewriting machine is fitted and by which it is supportable, said cabinet comprising a lower body-portion, and an 125 130

- upper cover-portion hinged thereto in rear, a slot intervening between the front of the cover and the top of the body, through which slot extend controlling devices from the carriage, said slot sealed in a manner to permit free travel of the carriage, said body-portion having a rear wall, a front wall, and overhanging side walls, all formed of a single rigid, unjointed die-cast shell making a continuous frame open at top and bottom, an opening being provided in said front wall between the top and bottom, through which the keyboard of the typewriter protrudes, said front wall unbroken at its top and also unbroken at its bottom, the typewriting machine being insertible downwardly and forwardly into the body in a manner to thrust the keyboard portion forwardly through said opening in the front wall, as set forth, said shell having integral means for locating the typewriting machine, and provision being made for lifting or supporting the encased typewriting machine by the casing.
16. The combination with a typewriting machine, of a sound-subduing cabinet within which the typewriting machine is fitted, and by which it is supportable, said cabinet comprising a lower body-portion, and an upper cover-portion hinged thereto in rear, a slot intervening between the front of the cover and the top of the body, through which slot extend controlling devices from the carriage, said slot sealed in a manner to permit free travel of the carriage, said body-portion having a rear wall, a front wall, and overhanging side walls, all formed of a single rigid, unjointed die-cast shell making a continuous frame open at top and bottom, an opening being provided in said front wall between the top and bottom, through which the keyboard of the typewriter protrudes, said front wall unbroken at its top and also unbroken at its bottom, the typewriting machine being insertible downwardly and forwardly into the body in a manner to thrust the keyboard portion forwardly through said opening in the front wall, as set forth, said shell having stiffening ribs, and sound-proof linings confined in place by said ribs.
17. The combination with a typewriting machine, of a sound-subduing cabinet within which the typewriting machine is fitted, and by which it is supportable, said cabinet comprising a lower body-portion, and an upper cover-portion hinged thereto in rear, a slot intervening between the front of the cover and the top of the body, through which slot extend controlling devices from the carriage, said slot sealed in a manner to permit free travel of the carriage, said body-portion having a rear wall, a front wall, and overhanging side walls, all formed of a single rigid unjointed die-cast shell making a continuous frame open at top and bottom, an opening being provided in said front wall between the top and bottom, through which the keyboard of the typewriter protrudes, said front wall unbroken at its top and also unbroken at its bottom, the typewriting machine being insertible downwardly and forwardly into the body in a manner to thrust the keyboard portion forwardly through said opening in the front wall, as set forth, the front open wall of said shell having at its top edge an integral stiffening rib, which rib also defines the lower edge of the slot for the traveling carriage handle, said slot being closed by a locally yielding tubular cushion, and said rib being shaped to serve as a depression, or seat for said cushion.
18. The combination with a typewriting machine, of a sound-subduing cabinet within which the typewriting machine is fitted, and by which it is supportable, said cabinet comprising a lower body-portion, and an upper cover-portion hinged thereto in rear, a slot intervening between the front of the cover and the top of the body, through which slot extend controlling devices from the carriage, said slot sealed in a manner to permit free travel of the carriage, said body-portion having a rear wall, a front wall, and overhanging side walls, all formed of a single rigid, unjointed die-cast shell making a continuous frame open at top and bottom, an opening being provided in said front wall between the top and bottom, through which the keyboard of the typewriter protrudes, said front wall unbroken at its top and also unbroken at its bottom, the typewriting machine being insertible downwardly and forwardly into the body in a manner to thrust the keyboard portion forwardly through said opening in the front wall, as set forth, the front open wall of said shell having at its top edge an integral stiffening rib, which rib also defines the lower edge of the slot for the traveling carriage handle, said slot being closed by a locally yielding tubular cushion, and said rib being shaped to serve as a depression, or seat for said cushion.
19. The combination with a typewriting machine, of a sound-subduing cabinet within which the typewriting machine is fitted, and by which it is supportable, said cabinet comprising a lower body-portion, and an upper cover-portion hinged thereto in rear, a slot intervening between the front of the cover and the top of the body, through which slot extend controlling devices from the carriage, said slot sealed in a manner to permit free travel of the carriage, said body-portion having a rear wall, a front wall, and overhanging side walls, all formed of a single rigid, unjointed die-cast shell making a continuous frame open at top and bottom, an opening being provided in said front wall between the top and bottom, through which the keyboard of the typewriter protrudes, said front wall unbroken at its top and also unbroken at its bottom, the typewriting machine being insertible downwardly and forwardly into the body in a manner to thrust the keyboard portion forwardly through said opening in the front wall, as set forth, the front open wall of said shell having at its top edge an integral stiffening rib, which rib also defines the lower edge of the slot for the traveling carriage handle, said slot being closed by a locally yielding tubular cushion, and said rib being shaped to serve as a depression, or seat for said cushion.

typewriter protrudes, said front wall unbroken at its top and also unbroken at its bottom, the typewriting machine being insertible downwardly and forwardly into the body in a manner to thrust the keyboard portion forwardly through said opening in the front wall, as set forth, the front open wall of said shell having at its top edge an integral stiffening rib, which rib also de-

fines the lower edge of the slot for the traveling carriage handle, said slot being closed by a locally yielding tubular cushion, and said rib being shaped to serve as a depression or seat for said cushion, and detachable means secured to said rib to operate therewith to embrace the cushion in part and hold it in place. 10 15
